[57] CLAIM

The ornamental design for a gas cylinder carrier, as shown and described.

DESCRIPTION

FIG. 1 is a perspective view of a gas cylinder carrier showing our new design;

FIG. 2 is a side elevational view thereof, the side not shown being a mirror image thereof;

FIG. 3 is a front elevational view thereof;

FIG. 4 is a rear elevational view thereof;

FIG. 5 is a top plan view thereof;

FIG. 6 is a bottom view thereof; and,

FIG. 7 is a side elevational view with a gas cylinder shown in broken lines to illustrate environmental structure.

FIG. 1

FIG. 2**FIG. 3**

FIG 4

FIG. 5***FIG. 6***

FIG. 7
